Primary Examiner — Susan Moon Lee

(57) CLAIM

I claim the ornamental design for a pet feeding station, as shown and described.

DESCRIPTION

FIG. 1 is a front, right perspective view of a pet feeding station showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The legs depicted in broken lines are an unclaimed feature of the pet feeding station and form no part of the claimed design.

1 Claim, 4 Drawing Sheets

FIG. 1

FIG. 2FIG. 3

FIG. 4FIG. 5

FIG. 6FIG. 7
